[57] CLAIM

The ornamental design for a pivotal chute, as shown and described.

DESCRIPTION

FIG. 1 is a perspective view of a pivotal chute showing my new design;

FIG. 2 is a right side elevational view;

FIG. 3 is a left side elevational view;

FIG. 4 is a front elevational view;

FIG. 5 is a rear elevational view;

FIG. 6 is a top plan view;

FIG. 7 is a bottom plan view;

FIG. 8 is a perspective view, shown in a condition of use;

FIG. 9 is a perspective view, shown in an alternate condition of use; and,

FIG. 10 is a perspective view thereof, shown in still another alternate condition of use.

FIGS. 1, 8-10 have all been drawn on an enlarged scale with respect to FIGS. 2-7.
